PARACHUTE

Filed Feb. 20, 1930

Inventor
A. Lehmann

By his Attorney
J. Federmann

UNITED STATES PATENT OFFICE

ALBERT LEHMANN, OF BROOKLYN, NEW YORK

PARACHUTE

Application filed February 20, 1930. Serial No. 429,895.

The main object of this invention is to provide a parachute which is made in the form of a bag into which a lifting gas is introduced.

5 Another object of the invention is to provide a parachute equipped with a bag exhausted by a valve and has a separate encircling conduit thereon. This conduit and bag are both adapted to be filled with some 10 lifting gas, such as helium, hydrogen and the like.

15 Still another object of the invention is to provide a parachute in the form of a closed bag having encircling conduit, both of which are filled through the hoses from a container which is strapped about the body of the person using the parachute.

20 A further object of the invention is to provide a parachute in the form of a bag which is encircled by a conduit, both the bag and conduit are adapted to be filled by some lifting gas and are provided with mechanism whereby the lifting gas may be valved out of the device.

25 The above and other objects will become apparent in the description below in which characters of reference refer to like named parts in the drawings.

Referring briefly to the drawings, Figure 30 1 is a longitudinal sectional elevational view through the parachute showing the means of transferring the gases from the tank to the tubes.

Figure 2 is a longitudinal sectional elevational view of the valve located in the gas bag.

Figure 3 is a longitudinal sectional elevational view of a valve coupling located in the bottom of the bag of the parachute.

40 Figure 4 is a perspective view showing the parachute in furled position in a sack mounted upon the gas container.

Figure 5 is a longitudinal sectional elevational view through the control valve in the gas container.

Referring in detail to the drawings, the numeral 10 indicates a hemispherical head, which is provided with a dome 11 and a concave under-roof 12. At the junction of the head 10 and roof 12, a conduit 13 circular in

cross section is formed. At arcuately spaced apart position on the area within the chamber 16 of the parachute, outlet valves are mounted on the conduit so that the gas when over normal pressure will valve into the 55 chamber 15 from the chamber 16 of the conduit. Suspended from the roof 12 is a flexible hose 17. This hose connects with the chamber 15 of the parachute and a manifold 20. The manifold has joined thereto a 60 plurality of tubes 18 which seat upon the carrying straps 19. The manifold is provided with a gas chamber 21, whose lower end opens as a threaded sleeve 22, the latter being engageable with a nipple or the like 65 upon the upper surface of a gas container 23. This gas container is draped on the breast of the wearer and is retained in such position by the harness bands 24 and 25. The manifold has communication with the 70 interior of the container 23 through a pipe 29, which is selectively opened or closed by a valve stem 27, having an opening 28 therein. The valve stem 27 is manipulated by a handle 26 in an obvious manner. The entire 75 parachute is rolled similar to a stocking and is slipped into a carrying bag 31.

The dome 11 of the parachute has mounted therein within the chamber 15 a valve body 32 in which a conical valve seat 80 33 is formed. The valve seat has normally contacting therewith a valve head 34 from which depends a stem provided with an eyelet 37. The seat passes through an enlarged opening in the body 32 of the valve and the 85 head 34 fits loosely in the chamber of the body, so that the gas may circulate freely through the valve body when the head 34 is lowered. The valve head is normally retained in contacting position with the seat 90 33 by a coil spring 35, which urges said head upwardly. The eyelet 37 of the valve stem 36 has a pull cord 38 secured thereto which extends to a leak-proof coupling illustrated in Figure 3, and located in the roof 12 of the 95 parachute. This coupling comprises a body 39 in which is located an upright conical seat 40 and an inverted conical seat 41. The conical seat 40 is adapted to have rested thereon a conical valve head 42, when the valve illus. 100

trated in Figure 2 is in open condition. The inverted seat 41 has normally seated thereon a valve head 43 when the pull cord 45 has not been manipulated. The valve head 43 is 5 lifted into contacting position on member 41 by a spring 47 which rests upon a flange 46 rigid in the valve body 49 upon a valve stem 44 connecting the valve head 42 and 43, a collar 48 is located. This collar is supported 10 by a coil string 47 which is wound about the stem 44 and rests upon the flange 46. The coupling for the pull cord is provided with a face plate 49 which is rigid with the body 39 and an auxiliary face plate 50 15 threadedly arranged on the body so that the coupling may be fitted in an aperture in the roof 12 of the parachute through these two members. The parachute is adapted to be rolled when in folded condition similar to a 20 stocking and is carried in the carrying bag 31. The entire contraption incuding the carrying harness by which the person is carried by the parachute, not shown on the drawings, is strapped to the body of the user. As 25 the user leaps out of a plane or the like from an altitude, the parachute is slipped from the bag and at the same time the valve handle 26 is manipulated. The compressed lifting gas carried in the container 23 then circulates 30 through the hose 17 and the plurality of tubes 18. The hose 17 fills the chamber 15 while the conduit chamber 16 is filled by the tubes 18. The parachute is so constructed that the speed of fall may be varied by valving 35 the gas from the chamber 15.

It is to be noted that the gas in entering the conduit chamber 16 will unfurl the entire head of the parachute and the superfluous amount of gas which passes into the chamber 16 is valved into chamber 15 through a 40 plurality of valve members 14. The chamber 15 is valved by manipulating the pull cord 45. A very slight movement is all that is necessary to valve the gas from the valve body 32. The pull cord 45 is attached to the upright and inverted valve heads 42 and 43 respectively through the medium of the stem 44. The coupling when the valve, illustrated in Figure 2, is closed, assumes the 45 position shown in Figure 3. As the pull cord 45 is lowered, the upper valve head 42 comes to rest upon the seat 40 and pull upon the cord 38 which is attached to the valve stem 36 of the gas valve through the medium 50 of the eyelet 37.

It is further to be noted that certain changes in form and construction may be made without departure from the spirit and scope of the invention.

60 I claim:

1. In a parachute, a hemispherical head, a conduit encircling said head, a hemispherical roof closing said head, a gas container, a hose connecting with the chamber in said head, said hose being adapted to be con-

nected to said container and openings in said conduit entering into the chamber in said head and means for valving gas out of said head.

2. In a parachute, a hemispherical head, a conduit encircling said head, a hemispherical roof closing said head, a gas container, a hose connecting with the chamber in said head, a plurality of tubes communicating with said conduit, a manifold suspended from said head and connected to said hose and tubes and means for valving said gas out of said head. 70

3. In a parachute, a hemispherical head, a conduit encircling said head, a hemispherical roof closing said head, a gas container, a hose connecting with the chamber in said head, said hose being adapted to be connected to said container and openings in said conduit entering into the chamber in said head, a plurality of tubes communicating with said conduit, a manifold suspended from said head and connected to said hose and tubes, a band suspended from said conduit adjacent said tubes, said bands being joined to said manifold, a valve for closing said container and a valve in said head, a pull string connected to said valve, a coupling passing through roof of said parachute having said pull strings attached thereto. 85

In testimony whereof I affix my signature.

ALBERT LEHMANN.
